UNITED STATES PATENT OFFICE.

EDWARD COOPER, OF NEWTON, MASSACHUSETTS, ASSIGNOR TO AMERICAN MICA COMPANY, OF NEWTON, MASSACHUSETTS, A CORPORATION OF MASSACHUSETTS.

MACHINE FOR FOLDING SHEETS OF MICA.

No. 890,500.

Specification of Letters Patent.

Patented June 9, 1908.

Application filed May 27, 1907. Serial No. 375,865.

To all whom it may concern:

Be it known that I, EDWARD COOPER, citizen of the United States, residing at Newton, in the county of Middlesex and Commonwealth of Massachusetts, have invented a certain new and useful Improvement in Machines for Folding Sheets of Mica, of which the following is a specification, reference being had therein to the accompanying drawings.

The invention relates to a new and useful improvement in machines for folding sheets of mica for insulating covers or linings or the like.

It is common to envelop the cores of electric meters with an insulating cover of mica and it is also common to form linings for commutators by folding sheets of mica. The mica commonly used for this purpose is made of sheets built up in the usual way and is folded into whatever form is required for the purpose intended. When used as a cover for a core, the core is usually a thin flat strip, and the cover is in form of a flattish tube formed by bending the sheet in proper form to receive the core. In order to make the sheet more flexible for folding, it is folded when warm.

The object of the present invention is to provide a machine by which the folding may be rapidly and cheaply and accurately performed.

In carrying out the invention, I provide mechanism by which the blank may be securely clamped to a holder with the blank projecting on two opposite sides, the holder with the blank clamped therein then being moved downward between two folding blocks which are engaged by the projecting portions of the blank on either side, thereby bending the oppositely projecting sides of the blank along the side lines where intended to be folded, and means by which the folding members are successively moved inward to first fold over one side of the blank upon the former and then to fold the other side of the blank down upon the first folded flap.

The invention will now be fully described, reference being had to the accompanying drawings, and the novel features will be pointed out and clearly defined in the claims at the close of the specification.

In the drawings,—Figure 1 is a plan of a machine embodying the invention. Fig. 2 is a vertical sectional elevation from front to

rear of the machine on line 2—2 of Fig. 1, showing a flat blank or sheet of mica on the holder or supporting plate before starting the operation of the machine. Fig. 3 is a vertical sectional elevation transversely of 60 the machine on line 3—3 of Fig. 1 before starting the operation. Fig. 4 is a section on the same line as Fig. 2 partly broken away, showing the parts as when the treadle is depressed sufficiently to bring the clamp into 65 contact with the blank. Fig. 5 is a section on the same line as Fig. 2 showing the treadle depressed sufficiently to bring the vertically movable support or holder block on which the blank is held into the recesses in the bed 70 plate. Fig. 6 is a section on the same line as Fig. 2 at a later stage in the operation than Fig. 5, showing one of the slideable folding members moved its full stroke inward to fold the side of the blank. Fig. 7 is a section on 75 the same line as Fig. 2, showing the second slideable folding member moved its full stroke. Fig. 8 is a perspective of the vertically movable support or block on which the blank is held, the clamp and folding members. Fig. 9 is a detail section showing the 80 stops for limiting the in and out movement of the folding members. Fig. 10 is a perspective of one of the folded blanks.

Referring to the drawings,—12 is a circulating water tank in the form of a hollow square supported on the standards 13. Resting on top of the water tank 12 is the bed plate 14. The purpose of the water tank is to keep the bed plate cool so as to cool the 90 blank as quickly as possible after being formed, and for this purpose the water in the tank is kept in circulation, entering through the pipe 15 and passing out through a pipe 16. The bed plate 14 is formed with a recess 85 17 in its upper side which is of exactly the right width and depth to receive the supporting plate or holding block 18 to which the blank 19 is to be clamped during the folding operation. The holding block 18 is 95 mounted fast on studs 20, 20, which extend downwardly through holes in the bed plate 14 within which they are vertically movable. These holes are enlarged from near the upper end to the bottom, forming recesses 22 within 100 which are held the coiled springs 23 which surround the studs 20, 20, the upper end of each spring 23 abutting against a pin 24 which passes transversely through the stud 20, the lower end of the spring being seated 110

on a collar 21 which is secured to the under side of the bed plate and through which the lower end of the stud 20 is free to pass.

Passing through the vertical holes in the bed plate 14 on opposite sides of the supporting plate 18 are the vertically movable rods or bars 25 which carry the clamping bar 26. Secured to the under side of the bed plate 14 are bracket hangers 27, the lower horizontal arm of which passes through a slot 39 in the rod 25, the slot 39 being elongated so as to permit vertical movement of the rod. Surrounding the rods 25 are coil springs 28, the upper end of each of which abuts against a pin 29 passing through the rod 25 and the lower end of which is seated upon the horizontal lower portion of the bracket 27. The springs 28 pressing up against the pins 29 normally hold the rods 25 in the position shown in Figs. 2 and 3, so that the clamping bar 26 will be held free from contact with the blank 19.

The rods 25 are connected with rods 30 in a manner to allow sliding action of one with relation to the other, the lower ends of the rods 30 being connected together by a cross bar 31 so that the bars 30 and cross bar 31 will move as one piece. In the form shown in the drawings, the slideable connection between the rods 25 and rods 30 is as follows: Each rod 25 is formed with an elongated slot 32, and each rod 30 is formed with an elongated slot 33. A bolt 34, which is pinned to the rod 30 as by a pin 35, passes through the upper portion of the elongated slot 32 in the rod 25. A bolt 36, which is pinned to the lower portion of the rod 25 as by a pin 37, passes through the lower portion of the elongated slot 33 in the rod 30, the rods 25 being normally held in their extended relation to each other, as shown in Figs. 2 and 3 by the coil springs 38, the upper end of each of which abuts against one of the bolts 34 and the lower end of which is seated on the bolt 36.

Mounted on the upper side of the water tank 12 on opposite sides of the bed plate 14 are folding members A and B, the two folding members being similar to each other, but means are provided by which their movements will be at different times from each other. These folding members are slideable on the top of the tank toward and from the bed plate 14.

Each folding member is bifurcated, having an upper jaw 41 and a lower jaw 42, forming a recess 43 to receive the bed plate 14 when the folding member moves forward, the bed plate being slotted at 44 on its under side to receive the lower jaw 42. The upper jaw 41 is formed also with a forwardly projecting lip 45, leaving a recess 46 between the lip 45 and the upper side of the bed plate 14 equal to the thickness of the article to be formed when it is folded.

Secured to the upper side of the cross bar 31 is a bracket 47 within which is journaled a pulley 48. Passing around this pulley 48 is a chain or cable 49, one end of which extends up over pulley 50 on the inner periphery of the water tank, thence up through a hole in the end wall of the folding member A, thence over pulley 51 secured to the outer wall of the water tank, and having at its end a weight 52. The other end of the cable 49 passes up over pulley 53 on the inner side of the water tank, thence through a hole in the end wall of the folding member B, thence down over pulley 54 and has at its end a weight 55. The weights 52 and 55 are unequal in amount for the purpose to be herein-after described.

The cable 49 is made fast to both of the folding members A and B. The method of fastening is not material. The means shown in the drawings are a pin 60 passing through the cable and bearing against the end of the folding member transversely of the hole through which the cable passes, so as to prevent the cable from being drawn through the block in one direction, and a perforated cap 61 through which the cable passes is secured to the outer face of the folding member and covering the pin 60, the pin bearing against said cap to prevent the cable from running through in the other direction.

Pivoted to a support 56 is a treadle 57 fulcrumed at 58 on a connecting rod 59, whose upper end is connected with the cross bar 31. By depressing the treadle 57, the cross bar 31 and the vertical rods 30 will be carried downward.

The springs 23, which surround the pins 20, and the springs 28 which surround the rods 25 are of less power than the springs 38. When the treadle is first depressed from the position shown in Figs. 2 and 3, it will depress the clamping bar 26 and compress the springs 28 until the clamping bar comes down into engagement with the blank 19 on the holding plate 18, and thereby clamping the blank firmly to the plate 18, as shown in Fig. 4. The continued depression of the treadle will carry down the rods 25 still further and also further compress the springs 28. It will also carry down the blank holding plate 18 until the plate 18 becomes seated in the recess 17 and thereby compress the springs 23. Until the plate 18 becomes seated in the recess 17, there will be no sliding movement of the rods 30 with relation to the rods 25 because the springs 38 are so much more powerful than the springs 28 and 23 that the rods 25 and 30 and connecting bar 31 will all move together as one frame.

When the holding plate 18 is moved from the position shown in Fig. 4 to the position shown in Fig. 5, seating the plate in the recess 17, the portions of the blank 19 which project beyond the sides of the holding plate

18 over onto the upper side of the folding members will be bent up as shown in Fig. 5. When, however, the plate 18 is seated in the recess 17, as shown in Fig. 5, the plate 18 can 5 have no further movement relative to the bed plate 14, the continued depression of the treadle will carry down the rods 30 and connecting rod 31 with relation to the rods 25, compressing the springs 38. In the mean- 10 time, the weight 52, being lighter than weight 55, will be raised rather than the weight 55 and as the cable 49 is made fast to the folding members A and B, the folding member A, which is connected with the lighter weight 52, 15 will be caused to move forward while the weight 55 and the folding member B remain stationary.

The forward movement of the member A will cause the lip 45 to engage the flap 19^a of 20 the blank and turn it over upon the clamp bar 26 which thereby serves as a former, or mold as shown in Fig. 6. The forward movement of the folding member A is limited by a stop pin 63 engaging with the bed plate 14. 25 In order to take the impact, a buffer 64 may be attached to the side of the bed plate.

In order to limit the rearward movement of the folding member on the reverse movement, it is provided with stops 65 which engage with stops 66. These stops 66 are preferably adjustable in and out to vary the 30 length of stroke possible to the folding member. As shown in the drawings, these stops 66 are screw threaded bolts which pass 35 through arms 67 which rise from the frame or side of the water tank.

When the folding member A is brought to a stop in its forward movement, the continued depression of the treadle will then cause 40 the weight 55 to rise and will move forward the folding member B to the position shown in Fig. 7. In so doing the projecting lip 45 will engage the flap 19^b of the blank and fold it over to meet or lap over the previously 45 folded flap 19^a. Preferably one of the flaps laps over farther than the other flap, the first folded flap 19^alapping over the farthest and extending farther over onto the clamping member 26 than does the lip 45 of the folding 50 member, so that when the flap 19^b is folded, it will lap over onto the first folded flap 19^a without engaging the lip 45 of the folding member A. This is shown clearly in Fig. 7.

As soon as both sides are folded, the pressure 55 will be released from the treadle, the weights will descend and both the folding members A and B will be carried back to their normal position and the folded blank will be removed from the clamping plate.

60 As the clamp bar 26 acts also as the form on which the blank is folded, it is important that it be so constructed and connected with the vertically movable rods 25 as to allow ready removal of the folded blank at the end 65 of the operation. One form of construction

and means for holding the clamp bar is that shown in the drawings. See Fig. 8. The vertical rods 25 are each in the form of a flat bar with lateral slots 70 extending from one edge in transverse direction of the rod and of sufficient width and depth to receive the clamp bar. The clamp bar 26 is pivoted near one end on a stud 71 rising from the bed plate 14, so that the clamp bar may be 70 swung around on the pivot far enough to release it from engagement with the vertical rods 25 or at least to release the swinging end of the clamp bar from engagement with the slot in the vertical rod, so that the blank may be pulled off over the free end of the clamp bar. It is not necessary to turn the clamp 75 far enough to entirely withdraw it from the slot nearest the pivoted end, therefore, it will be supported by the pivot and the slot at that end as shown in dotted lines Fig. 1.

In order that the clamp bar may be guided back to the interior of the slot 70 and prevented from turning on its pivot to become disengaged during its downward movement, a short guide pin 72 is provided which rises 80 from the bed plate in such position as to be engaged by the clamp plate after it has partially descended. This guide pin does not rise high enough to interfere with the swinging of the clamp bar on its pivot when the vertical rods are at their full elevation in order to release the clamp plate and remove the blank, but does rise high enough so as to engage the edge of the clamp bar almost as soon as it begins its descent as will be seen 85 by reference to Fig. 8. The upper end of the said pin 72 is preferably bent outward at an angle for the pin to engage the edge of the clamp bar in case it is not fully moved back to proper position before it begins its descent. 90

In order to provide a guide and stop for the blank when it is first placed upon the supporting plate before it is clamped, so that the blank will be adjusted to exactly the right position, a gage plate 73, see Fig. 8, is 95 secured to the upper side of the folder B on the side opposite to that from which the blank is inserted. The blank will be shoved in under the clamp bar until its edge strikes true with the edge of the gage plate 73 and 100 held there by hand until the treadle is depressed sufficiently to bring the clamp bar into engagement with the blank. The plate 73 is preferably adjustably connected with the bed plate so that the blank may be 105 moved in a greater or less distance as may be required to regulate the width of the flap 19^b. To provide for this, the guide plate 73 is formed with transversely elongated slots 74 and the guide plate is clamped to the bed 110 plate by clamp screws 75 which pass through these guide slots and are screwed into holes tapped out in the bed plate.

115 It is obvious that while I have described the machine as provided with two folding 120

members to fold two opposite sides of the blank, when if for any purpose it is desired to fold a blank on one side only, the machine would in that case require to have only one folding member and a machine thus provided would embody my invention.

I claim as my invention:

1. In a machine for folding sheets of mica or the like, a supporting plate for the blank while being folded, a clamp plate which serves as a former on which the blank is to be folded, means for actuating said clamp plate, a pair of oppositely disposed folding members, means for actuating the folding members, a tension device connected with each of said folding members, one of said tension devices being more powerful than the other, whereby the folding member having the weaker tension device will be actuated before the other.

2. In a machine for folding sheets of mica or the like, a vertically movable support for the blank, a clamp plate which also serves as a former for the blank while being folded and is of less width than the blank which is to be folded, a spring seat for said support, a bed plate having a recess adapted to receive said clamp plate when it is depressed, vertically movable supports for said clamp plate, each consisting of two members having slidable relation with each other, springs which normally hold said two members of each vertical support in fixed relation to each other, said springs being more powerful than the springs for said supporting plate, mechanism for depressing said vertical supports, oppositely disposed folding members for said blank, a flexible connection between said vertically movable supports and said folding members, whereby the operation of said depressing mechanism will actuate said folding members.

3. In a machine for folding sheets of mica or the like, a vertically movable supporting plate for the blank, a spring seat for said supporting plate, a bed plate having a recess adapted to receive said supporting plate when it is depressed, a clamp plate, vertically movable supports for said clamp plate, each of said movable supports consisting of two members having slidable relation with each other, springs which normally hold said two members in fixed relation with each other and are more powerful than the springs connected with said vertical supports, mechanism whereby the same may be depressed, oppositely disposed folding members, a flexible connection between said vertical supports and each of said folding members, whereby the operation of said depressing mechanism will cause the descent of said clamp against the blank upon the supporting plate and then cause the descent of the supporting plate and blank clamped thereto until seated in the said recess and the continued

operation of the depressing mechanism will actuate said folding members, a tension device connected with each of said folding members, one of said tension devices being stronger than the other, whereby the folding member having the weaker tension device will be actuated before the other, the continued operation of the depressing mechanism after the first folding member has come to a stop actuating the second folding member.

4. In a machine for folding sheets of mica or the like, a vertically movable supporting plate for the blank, a spring seat for said supporting plate, a bed plate having a recess adapted to receive said supporting plate when it is depressed, a clamp plate, vertically movable supports for said clamp plate, each of said movable supports consisting of two members having slidable relation with each other, springs which normally hold said two members in fixed relation with each other and are more powerful than the springs connected with said vertical supports, a treadle connected with said vertical supports whereby the same may be depressed, oppositely disposed folding members, a flexible connection between said vertical supports and each of said folding members, whereby the depression of said treadle will cause the descent of said clamp against the blank upon the supporting plate and then cause the descent of the supporting plate and blank clamped thereto until seated in the said recess and the continued depression of the treadle will actuate said folding members, a tension device connected with each of said folding members, one of said tension devices being stronger than the other, whereby the folding member having the weaker tension device will be actuated before the other, the continued descent of the treadle after the first folding member has come to a stop actuating the second folding member.

5. In a machine for folding sheets of mica or the like, a vertically movable supporting plate for the blank, a spring seat for said supporting plate, a bed plate having a recess adapted to receive said supporting plate when it is depressed, a clamp plate, vertically movable supports for said clamp plate, each of said movable supports consisting of two members having slidable relation with each other, springs which normally hold said two members in fixed relation with each other and are more powerful than the springs connected with said vertical supports, a treadle connected with said vertical supports whereby the same may be depressed, oppositely disposed folding members, a flexible connection between said vertical supports and each of said folding members, whereby the depression of said treadle will cause the descent of said clamp against the blank upon the supporting plate and then cause the descent of the supporting plate and blank clamped thereto until seated in the said recess and the continued

thereto until seated in the said recess and the continued depression of the treadle will actuate said folding members, a weight having a flexible connection with each of said folding members, the weight which is connected with one of the folding members being heavier than that which is connected with the other, whereby the depression of said treadle will actuate first the folding member which has the lesser weight attached thereto, a stop which limits the forward movement of said first folding member, whereby the continued depression of said treadle will actuate the second of said folding members.

15. 6. In a machine for folding sheets of mica or the like, a vertically movable supporting plate for the blank, a clamp plate pivoted at one end, which also serves as a former for the blank while being folded, vertically movable rods with which said clamp plate is detachably connected, said vertically movable rods being slotted to receive said clamp plate when it is turned on its pivot, a bed plate having a recess adapted to receive said supporting plate when it is depressed, means for depressing said vertically movable rods and thereby also the clamp plate, said clamp plate in its descent clamping the blank against the supporting plate and causing the descent also of the supporting plate, blank and clamp together, folding mechanism and a connection between said folding mechanism and said vertically movable rods whereby the movement of the vertical rods actuates the folding mechanism.

30. 7. In a machine for folding sheets of mica or the like, a vertically movable supporting plate for the blank, a clamp plate pivoted at one end, which also serves as a former for the blank while being folded, vertically movable rods with which said clamp plate is detachably connected, said vertically movable rods being slotted to receive said clamp plate when it is turned on its pivot, a bed plate having a recess adapted to receive said supporting plate when it is depressed, means for depressing said vertically movable rods and thereby also the clamp plate, said clamp plate in its descent clamping the blank against the support-

ing plate and causing the descent also of the supporting plate, blank and clamp together, folding mechanism and a connection between said folding mechanism and said vertically movable rods whereby the movement of the vertical rods actuates the folding mechanism and an adjustable gage plate to aid in adjusting the blank to proper position before it is engaged by the clamp.

10. 8. In a machine for folding sheets of mica or the like, a vertically movable supporting plate for the blank, a clamp plate pivoted at one end, which also serves as a former for the blank while being folded, vertically movable rods within which said clamp plate is detachably connected, said vertically movable rods being slotted to receive said clamp plate when it is turned on its pivot, a bed plate having a recess adapted to receive said supporting plate when it is depressed, means for depressing said vertically movable rods and thereby also the clamp plate, said clamp plate in its descent clamping the blank against the supporting plate and causing the descent also of the supporting plate, blank and clamp together, folding mechanism and a connection between said folding mechanism and said vertically movable rods whereby the movement of the vertical rods actuates the folding mechanism, and a guide rod which is engaged by the clamp plate in its descent.

20. 9. In a machine for folding sheets of mica or the like, a vertically movable supporting plate for the blank, a clamp plate which also serves as a former for the blank while being folded, a bed plate adapted to receive said supporting plate when it is depressed, an adjustable gage plate to guide in adjusting the blank on the supporting plate before the blank is clamped to the supporting plate, means for actuating the clamp, and folding mechanism adapted to fold the projecting side of the blank.

In testimony whereof I affix my signature, in presence of two witnesses.

EDWARD COOPER.
